UNITED STATES PATENT OFFICE.

FRANK McINTYRE, OF NEW YORK, N. Y.

SCREW-CAP FOR COLLAPSIBLE TUBES.

944,203:

Specification of Letters Patent. Patented Dec. 21, 1909.

Application filed February 19, 1909. Serial No. 478,859.

To all whom it may concern:

Be it known that I, FRANK McINTYRE, of the city, county, and State of New York, have invented a certain new and useful Improvement in Screw-Caps for Collapsible Tubes, of which the following is a specification.

It is the object of this invention to provide a screw cap for collapsible tubes which need not be removed from the neck of the tube in order to permit the contents of the latter to be squeezed out. I am aware that this is not broadly new with me.

My invention consists in a construction for that purpose which will first be described in connection with the accompanying drawings, and will then be more particularly pointed out in the claim.

In the drawings—Figure 1 is a perspective view of a collapsible tube and screw cap embodying my invention. Fig. 2 is an axial section of the same with the cap screwed down so as to close the tube.

A is a collapsible tube of any known or preferred construction; B is its externally screw threaded tubular neck; and C is the internally threaded cap which screws upon the neck.

The neck B is of cylindrical exterior and has its outer end closed by a head b, on which there is a central knob b² of half round or equivalent shape. The head b is pierced by perforations b'—in this instance three in number—which are arranged around the base of the knob at equal distances apart. The cap C—the walls of which fit closely around the neck so as to leave no lateral space between it and the neck—has in it a circular central opening c' which is entered and filled by the knob b² when the cap is screwed home. The top of the cap screws

down quite close upon the head b so as to leave practically no space either on the top or the sides of the neck B in which the contents of the tube can gather. When the cap is screwed home the knob b² on the head b closes the hole c' in the cap C at the same time that the top of the cap closes the holes b' in the head b. Thus so long as the cap is screwed down, the tube A is closed against any escape of its contents through the holes b', and is practically sealed. At the same time, a half turn of the cap from this position will suffice to open the holes b' c', to allow the material to be squeezed out, the same passing out through the narrow annular slit between the margin of the opening c' and the knob b², and assuming the form of a solid cylinder as it passes beyond the latter.

The device is cheap, simple and efficient; and the tube is sealed perfectly when the cap is screwed home.

What I claim herein as new and desire to secure by Letters Patent is—

A collapsible tube having a cylindrical screw threaded neck closed at its outer end by a solid head provided with holes b' in the end thereof and a central knob b², and a screw threaded cap having in its top a central hole c' to receive the knob b², the arrangement being such that when the cap is screwed home it will close the holes b' in the head, while, in turn, its hole c' will be closed by the knob b², substantially as and for the purposes hereinbefore set forth.

In testimony whereof I affix my signature in presence of two witnesses.

FRANK McINTYRE.
